UNITED STATES PATENT OFFICE.

CALVIN A. SWEET, OF YANKTON, SOUTH DAKOTA.

HANGER.

1,156,380.

Specification of Letters Patent. Patented Oct. 12, 1915.

Application filed October 29, 1913. Serial No. 798,090.

To all whom it may concern:

Be it known that I, CALVIN A. SWEET, a citizen of the United States, residing at Yankton, in the county of Yankton and State of South Dakota, have invented certain new and useful Improvements in Hangers, of which the following is a specification, reference being had to the accompanying drawings.

10 This invention relates to new and useful improvements in hangers and more particularly to the class designed for the purpose of suspending telephone cables, from what is commonly called a messenger cable, it being understood, however, in this connection that the hanger may be used for suspending cable other than the telephone cable from a support, other than the messenger cable.

15 The object of the present invention is the provision of a hanger of the above character which is of such construction that it can be readily applied to or detached from a support without the use of any tools.

20 A further object of this invention is the provision of a hanger of the above type which will possess advantages in points of efficiency and durability, is inexpensive of manufacture and at the same time is simple in construction and operation.

25 With the above and other objects in view, this invention consists in the novel features of construction and the combination and arrangement of parts to be hereinafter more fully described, pointed out in the claim and 30 shown in the accompanying drawings, in which—

Figure 1 is a front elevation of a hanger constructed in accordance with my invention and illustrating the application of the same; 35 Fig. 2 is a side elevation; Fig. 3 is a top plan view.

40 Referring more particularly to the drawing, the numeral 10 indicates a messenger cable, below which is suspended the telephone cable 11 by means of the hanger 12. These hangers are formed from a single strand of wire bent to produce an inclined body portion 13, the lower end thereof being curved to provide an attaching eye 14. 45 The opposite end of this body portion 13 is bent to form a curved loop or supporting convolution 15, the terminal of which is re-curved, as at 16, to produce a terminal convolution 17 arranged in spaced relation with

the supporting convolution 15 and adapted 55 to rest upon the upper face of the messenger cable.

The convolutions 15 and 17 are spaced apart a distance slightly greater than the diameter of the messenger cable 10, as clearly 60 shown in the drawing, for a purpose which will be hereinafter more fully set forth.

In the application of my improved hanger, the same is attached to the cable 11 in the following manner:—The flexible attaching members 18 are passed through the attaching eye 14 and looped around the cable 11. The attachment of the messenger cable 10 is made in the following way:—The axis 65 of the convolutions 15 and 17 is turned at 70 right angles to the axis of the messenger cable 10, the hanger being held above the messenger cable 10, with the convolutions 15 and 17 on the lower side, the hanger is then passed downward, the convolution 15 passing 75 on one side of messenger cable 10 and convolution 17 passing on the other side of the messenger cable 10, until a portion of convolutions 15 and 17 comes to rest on the messenger cable 10, the hanger is then 80 turned so that the axis of the convolutions 15 and 17 is parallel to the axis of the messenger cable 10, and the hanger with cable 11 attached allowed to take its natural position as shown in the accompanying drawings, convolution 15 resting on the top side 85 of messenger cable 10.

From the foregoing description taken in connection with the accompanying drawings, it will be obvious that a hanger of the 90 nature described is provided which will fulfil all of the necessary requirements of such a device. As shown in Fig. 1 of the drawings, the convolution 17 can be arranged upon either side of the convolution 15 as the 95 various uses to which the hanger is to be put will necessitate.

While I have shown and described the preferred form of my invention, it will be obvious that various changes in the details of 100 construction and in the proportions may be resorted to for successfully carrying my invention into practice without sacrificing any of the novel features or departing from the scope of the appended claim.

105 What I claim is:—

A hanger including a body, a helical convolution formed at one end thereof, that por-

tion of the convolution which is adapted to sustain the pull upon the hanger being in the same plane with the body thereof, and an eye formed at the other end of the body, 5 said eye being disposed in the plane of the body member and at right angles to the axis about which the convolution is wound.

In testimony whereof I hereunto affix my signature in the presence of two witnesses.

CALVIN A. SWEET.
